US00D783847S

(12) **United States Design Patent** (10) Patent No.: **US D783,847 S**
(45) Date of Patent: **** Apr. 11, 2017**

(54) **BASE FOR A PEDICURE FOOT SPA**

D227,952 S 7/1973 Costabile et al.
3,881,471 A 5/1975 Grube
4,238,097 A 12/1980 Clausen et al.
D262,911 S 2/1982 Weddell
4,497,313 A 2/1985 Kurosawa
D282,609 S 2/1986 Stulik
4,620,529 A 11/1986 Kurosawa

(71) Applicant: **Continuum Footspas, LLC**, New Berlin, WI (US)

(Continued)

(72) Inventors: **Joseph J. Galati, Jr.**, Brookfield, WI (US); **John Meyerovich**, Bal Harbour, FL (US)

FOREIGN PATENT DOCUMENTS

(73) Assignee: **Continuum Footspas, LLC**, Brookfield, WI (US)

CM 34417548 2/2005
CN 302384546 4/2013

(**) Term: **15 Years**

(21) Appl. No.: **29/535,303**

(22) Filed: **Aug. 5, 2015**

(51) LOC (10) Cl. **24-04**

(52) U.S. Cl.

USPC **D24/204**

(74) Attorney, Agent, or Firm — Ryan Kromholz & Manion, S.C.

(57) **CLAIM**

The ornamental design for a base for a pedicure foot spa, as shown and described.

DESCRIPTION

FIG. 1 is a front perspective view of our invention;

FIG. 2 is a rear perspective view;

FIG. 3 is a right side elevation view;

FIG. 4 is a left side elevation view;

FIG. 5 is a top plan view;

FIG. 6 is a bottom plan view;

FIG. 7 is a front elevation view; and,

FIG. 8 is a rear elevation view.

The broken lines in FIG. 6 represent the bounds of the claim and form no part of the claimed design.

1 Claim, 3 Drawing Sheets
